CLAIM

The ornamental design for a carrying case, as shown and described.

DESCRIPTION

FIG. 1 is a top perspective view of a carrying case showing my new design;

FIG. 2 is a top plan view thereof;

FIG. 3 is a front elevation thereof;

FIG. 4 is a bottom plan view thereof;

FIG. 5 is a rear elevation thereof; and

FIG. 6 is a right side elevation thereof; the left side elevation being a mirror image thereof.

FIG.1.

FIG.2.

FIG.3.

FIG.4.

FIG.5.

FIG. 6.
